UNITED STATES PATENT OFFICE.

JAFEW S. VAN BUREN, OF ALBANY, NEW YORK.

STOVE-TOP.

1,170,857.

Specification of Letters Patent.

Patented Feb. 8, 1916.

Application filed April 22, 1915. Serial No. 23,251.

To all whom it may concern:

Be it known that I, JAFEW S. VAN BUREN, a citizen of the United States, residing at Albany, in the county of Albany and State of New York, have invented certain new and useful Improvements in Stove-Tops; and I do declare the following to be a full, clear, and exact description of the invention, such as will enable others skilled in the art 10 to which it appertains to make and use the same.

My invention relates broadly to improvements in stoves and ranges, and more particularly to tops therefor.

Heretofore, numerous types of stoves have been provided with tops having gratings disposed above the various burners thereof, and it has been the general policy to furnish cover plates with such stoves, whereby the 20 grates may be covered when desired, thus preventing the flame from the burners from rising therethrough.

Some types of gratings are disposed below the plane in which the top of the stove is located, while others project above such a plane. The result is that utensils cannot be readily moved over the top of the stove, since obstructions are encountered. Furthermore, these obstructions are much more 30 noticeable when the cover plates are applied to use, since they usually project above the plane in which the top of the stove is disposed. This often causes such plates to be dislocated by the shifting of a utensil upon 35 the stove.

It is to overcome the difficulties above briefly set forth, that I have designed the construction constituting the subject matter of the present invention, such construction 40 being hereinafter described and claimed.

In describing the invention, I shall refer to the accompanying drawing wherein like reference characters designate corresponding parts throughout the various views and 45 wherein:—

Figure 1 is a plan view of a stove top constructed in accordance with the invention; said top being shown as having two gratings to one of which a cover plate is applied; Fig. 2 is a vertical transverse section as seen along the plane indicated by the line 2—2 of Fig. 1; and Fig. 3 is a bottom plan view of one of the cover plates.

In this drawing, constituting a part of 55 the application, 1 designates a rectangular plate constituting the top of the stove, this

plate having one or more circular openings 2 which, when the plate 1 is applied to use, are disposed over the burners of the stove. The plate 1 is shown in the present embodiment as provided with two of the openings 2 and with a third and smaller opening 3 disposed therebetween and provided with a removable lid 4.

Substantially spanning the two openings 60 2, are the gratings which are here shown in the form of a plurality of radially extending fingers 5 whose outer ends are integrally joined to lugs 6 which depend from the plate 1 adjacent the edges of the openings 2 70 therein. As clearly shown in Fig. 2, the upper sides of the gratings lie in the same plane in which the upper side of the plate 1 is disposed, this being advantageous in order to allow utensils to be more readily moved 75 upon the top of the stove. The outer ends of the fingers 5 constituting said gratings, however, are provided with notches 7 in their upper sides, the inner end walls of said notches being preferably inclined upwardly 80 and inwardly as seen at 8 while the outer end walls thereof preferably, though not necessarily, incline in the opposite direction.

Operating in conjunction with the gratings, are the cover plates 9, such plates having their peripheral edges beveled downwardly and inwardly for contact with the inclined outer walls of the notches 7, while at suitable points spaced around the circumference of said plates 9, depending feet or 85 the like 10 are provided, these various feet having inclined inner sides 11 abutting the inclined inner end walls 8 of the notches 7 when the plates are applied to use. Leading inwardly from the various feet 10, to points 90 near the center of the plates 9, are the slots 12, these slots receiving the upper edges of the fingers 5 when the plates are used as shown in Figs. 1 and 2. During such use, it is to be observed that the feet 10 rest upon 100 the bottom walls of the notches 7 and that they are of such height as to support the plates 9 in such positions as to cause their upper sides to lie in the same plane in which the upper side of the top plate 1 is disposed. 105 It will thus be seen that even though the plates 9 must be necessarily used at times, they will afford no obstruction whatever to the passage of utensils over the top of the stove.

In the foregoing, I have described certain specific details of construction for producing

probably the best results, and in the drawings I have shown such details. It will be evident, however, that I need not be limited thereto otherwise than to the extent to which 5 the appended claims limit me. In the present application, I have shown the upper edges of the fingers 5 rising through the slots 12 in the cover plates in order to prevent shifting of said plates in respect to said 10 fingers, but I do not wish to be confined to this specific construction, it being evident that other types of projections rising into the slots in the cover plate could well be provided for accomplishing the same results.

15 From the foregoing description, taken in connection with the accompanying drawing, it will be evident that although extremely simple construction has been provided for carrying out the object of the invention, the 20 latter will be very efficient in operation and will possess a number of highly advantageous features.

I claim:

1. The combination with a stove top having 25 a grating, of a cover plate covering said grating and having slots receiving portions thereof.

2. The combination with a stove top having a grating, of a cover plate covering said 30 grating and having slots receiving portions thereof, the upper side of the plate being disposed in the plane in which the top of the stove is disposed.

3. The combination with a stove top having 35 a grating whose upper side lies in the plane in which the upper side of the top lies, of a cover plate having slots receiving portions of said grating, the upper side of said plate being disposed in the aforesaid plane.

40 4. The combination with a stove top hav-

ing therein an opening, and a grating substantially spanning said opening and including a plurality of radially disposed fingers provided with notches in their upper sides, of a cover plate having depending feet received by said notches. 45

5. The combination with a stove top having therein an opening, and a grating substantially spanning said opening and including a plurality of radially disposed fingers 50 having notches in their upper sides and having said upper sides disposed in the plane in which the upper side of the top is disposed; of a cover plate covering said grating and having a plurality of radial slots receiving the radial fingers, and feet depending from the cover plate into the aforesaid notches and supporting said plate at a level in which its upper side is located in the same plane in which the upper side of the top lies. 55

6. The combination with a stove top having an opening therein, and a cover plate closing said opening and having a plurality of apertures, of rigid supporting projections rising into the aforesaid apertures for the 60 purpose set forth.

7. The combination with a stove top having therein an opening and a grating substantially spanning said opening; of a cover plate closing the opening and having a plurality of apertures, and rigid projections rising from the aforesaid grating into said 70 apertures.

In testimony whereof I have hereunto set my hand in presence of two subscribing witnesses. 75

JAFEW S. VAN BUREN.
